UNITED STATES PATENT OFFICE.

WILLIAM W. TAYLOR, OF COLUMBUS, OHIO.

DESIGN FOR A DEVICE FOR SHARPENING FISH-HOOKS.

53,645.

Specification for Design.

Patented July 22, 1919.

Application filed March 26, 1919. Serial No. 285,390. Term of patent 14 years.

To all whom it may concern:

Be it known that I, WILLIAM W. TAYLOR, a citizen of the United States, residing at Columbus, in the county of Franklin and State of Ohio, have invented a new, original, and ornamental Design for a Device for Sharpening Fish-Hooks, of which the following is a specification, reference being had to the accompanying drawing, forming part thereof.

In the drawing, Figure 1 is a view in perspective of my newly designed sharpening device, and Fig. 2 is an end view of the same.

I claim:

The ornamental design for a device for sharpening fish hooks, as shown.

WILLIAM W. TAYLOR.
